AND TOOTH PASTE HOLDER OR SIMI-LAR ARTICLE

Howard R. Sigler, Argenta, and Carl A. Laystrom,
Decatur, Ill., assignors, by mesne assignments,
to Fairies Manufacturing Company, Chicago,
Ill., a corporation of Illinois

Application December 13, 1947, Serial No. 143,124

Term of patent 14 years

(Cl. D4—3)

To all whom it may concern:

Be it known that we, Howard R. Sigler and Carl A. Laystrom, both citizens of the United States and residents of the city of Argenta, in the county of Macon and State of Illinois, and of the city of Decatur, in the county of Macon and State of Illinois, respectively, have jointly invented a new, original, and ornamental Design for a Combined Toothbrush and Tooth Paste Holder or Similar Article, of which the following is a specification, reference being had to the accompanying drawing, forming a part thereof.

On the drawing:

We claim:

The ornamental design for a combined toothbrush and tooth paste holder or similar article, as shown and described.

HOWARD R. SIGLER.
CARL A. LAYSTROM.
